WILLIAM ROCKWELL CLOUGH, OF ALTON, NEW HAMPSHIRE.

BOTTLE ATTACHMENT.

1,120,906.

Specification of Letters Patent. Patented Dec. 15, 1914.

Application filed April 6, 1911. Serial No. 619,208.

To all whom it may concern:

Be it known that I, WILLIAM ROCKWELL CLOUGH, a citizen of the United States, and a resident of Alton, in the county of Belknap and State of New Hampshire, have invented certain new and useful Improvements in Bottle Attachments, of which the following is a specification.

The invention resides in means suitably connecting a cork-screw with the cork of a bottle and allowing the cork-screw to hang downwardly parallel with the bottle-neck, and the object of the invention is to provide convenient means for so connecting a cork-screw with the bottle with which it is to be ultimately used that the corkscrew will not become detached or lost during the handling, packing or shipment of the bottle or its display or handling when in the possession of the retailer.

I contemplate more particularly the connection to bottle-corks of the one-piece wire corkscrews of the general class described and shown in Letters Patent No. 161,755 granted to me on April 6, 1875, many millions of which corkscrews are and for years have been manufactured and sold annually. The subject of the temporary connection of these corkscrews to bottles with which they are finally to be used, has received considerable thought, and while several means have been suggested to meet the well recognized want, it is known in the trade that no very satisfactory means for thus securing the corkscrews has heretofore gone into use, the most usual expedient for connecting the corkscrews to bottles being rubber bands applied to bind the corkscrews against the bottles. The use of rubber bands for the purpose avoids the employment of strings, wires and the like, but they are nevertheless insecure and leave the corkscrews projecting in all directions and are otherwise unsatisfactory.

My invention has for its purpose to temporarily connect the corkscrew with the cork of the bottle and to provide means by which this may be expeditiously and efficiently accomplished in a manner leaving the bottles with their connected attachments and corkscrews uniform in appearance and capable of being conveniently packed and shipped or otherwise handled.

I utilize the material of the cork itself as one element of the means for connecting the corkscrew to the bottle, and as a further

element of said means I provide an attaching member comprising a body to be detachably secured at its inner end to the cork and having at its outer end a reversely turned part creating a loop to receive and hold the ring of a corkscrew and allow the latter to hang therefrom at the side of the bottle-neck, said loop being, when in use, closed at its inner or entrance end by the top of the cork or the side of the cork or the side of the lip of the bottle or otherwise so that the corkscrew may not be jarred therefrom.

The invention will be fully understood from the detailed description hereinafter presented, reference being had to the accompanying drawings, in which:

Figure 1 is a central vertical section, partly broken away, through a bottle and its cork or stopper equipped with a corkscrew holding attachment embodying my invention; Fig. 2 is a top view of the same; Fig. 3 is a detached perspective view of the attachment for connecting the corkscrew with the cork; Fig. 4 is a like view of a modified form or outline of the same; Fig. 5 is a view corresponding with Fig. 1 but showing a modified form of the attachment in which the inner or entrance end of the loop is closed by the side of the cork; Fig. 6 is a like view of a further modification of the invention in which the inner end of the loop member is closed by the side of the lip of the bottle; Fig. 7 is a detached top view of the attachment shown in Fig. 6; and Fig. 8 is a side elevation, partly broken away, of a further modified form of attachment embodying my invention in its broader scope.

In the drawings, 10 designates a bottle or flask of known character having a neck 11 and lip 12 and, as shown, closed by a cork 13 with which, referring to Figs. 1, 2 and 3, by means of a suitable attachment 14, a cork-screw 35 intended for ultimate use in extracting the said cork, is connected. The bottle 10, cork 13, and corkscrew 35 are of usual or suitable form and construction. The attachment or connection 14, referring to Figs. 1, 2 and 3, is in one integral piece of sheet metal comprising a horizontal body portion 15, a prong 16 extending downwardly from the inner end thereof and embedded in the cork 13, and a reversely bent loop-member 17 extending inwardly from the outer end of and below said body portion and terminating above the cork 13,

whereby a loop 18 is created to receive the ring of the corkscrew 35 and permit the latter to hang downwardly at the side of the neck of the bottle. By reason of the inner 5 end of the loop-member 17 being above the cork 13 and, with the body portion 15, pressed downwardly against the same, the inner or entrance end to the loop 18 is effectually closed and the corkscrew prevented 10 from escaping therefrom until the attachment 14, when the bottle is in the hands of the consumer, is detached from said cork. The body portion 15 of the attachment extends horizontally beyond the edge of the 15 bottle-lip 12 so that the corkscrew may hang suspended therefrom in close relation to the side of the bottle-neck. Preferably the attachment 14 is in one integral piece of sheet tin and the body-portion 15 thereof is 20 preferably approximately of elliptical outline so as to afford an adequate plane surface against which the pressure of the thumb may be exerted in driving the prong 16 into the cork 13.

25 In assembling the parts the ring or handle of the corkscrew is inserted in the loop 18 and then the attachment 14 is applied to the cork 13 by pressing the prong 16 downwardly into the upper end thereof until the 30 inner end of the loop-member 17 and body 15 are close against the top of the cork, and thereupon the corkscrew will have been securely, though detachably, connected with the cork and also with the bottle provided 35 the cork is in the bottle at the time the attachment 14 and corkscrew 35 are applied thereto. The attachment 14 and corkscrew 35 may be applied to the cork either before or after the cork is inserted in the bottle- 40 mouth.

The attachment 14 is comparatively inexpensive of construction and may not only be conveniently applied to the cork 13 for effectually connecting the corkscrew to the 45 bottle but readily detached therefrom so as to release the corkscrew and permit its use in extracting the cork from the bottle. When the bottle is in the hands of the consumer, the attachment 14 may be withdrawn 50 from the cork and the corkscrew released from said attachment and screwed into the cork for use in extracting the cork in the usual way.

In Fig. 4 the attachment is shown as having plane parallel or straight edges in its 55 body portion in lieu of the oppositely convexed edges presented in Fig. 3. The attachment shown in Fig. 4 being a modification, I number the body portion thereof 19, 60 its prong 20 and its loop-member 21.

In Fig. 5 the attachment is shown as made from a rod of wire bent to form the body portion 22, prong 23 and loop-member 24, and in this instance the inner end of 65 the loop-member instead of being on the top

of the cork 13 terminates adjacent to the side thereof and above the lip-edge of the bottle, the loop being thereby closed to retain the corkscrew. The cork of Fig. 5 projects above the lip-edge of the bottle, and hence the inner end of the loop-member 24 70 may extend inwardly to the side thereof for closing the loop instead of upon the top of the cork in the manner shown in Figs. 1 and 2.

75 In Figs. 6 and 7 I show the attachment as modified from the construction illustrated in Fig. 1 to the extent of having the loop-member 25 in said Figs. 6 and 7 terminate at its inner end adjacent to the side of the 80 bottle-lip 12, whereby said lip is enabled to cooperate with said member in securely confining the corkscrew.

In Fig. 8 the modification there shown consists in having the loop-member 26 85 turned inwardly over the body portion of the attachment instead of under the same as in the preferred construction. The member 26 at its inner end will be in close relation to the body of the attachment so as to confine 90 the corkscrew and when pressed upwardly, as on the insertion of the corkscrew-ring thereunder, will spring back to its initial position so as to close the loop. The loop-member in Fig. 1 also closes automatically. 95

In all of the constructions shown, the attachment serves to connect the corkscrew with the bottle, the cork being the means for securing the attachment to the bottle, and in all said constructions the attachment may be 100 applied to the cork with the prong driven centrally therein or in such location in accordance with the thickness of the glass in the bottle as will enable the loop to properly project beyond the outer vertical plane of 105 the bottle-lip and permit the corkscrew to hang therefrom at the side of the neck of the bottle.

My invention dispenses entirely with the use of rubber bands, strings and the like for 110 temporarily connecting corkscrews to bottles and its use requires no change either in the well-known construction of corkscrew or in the bottle with which it is to be used.

What I claim as my invention and desire 115 to secure by Letters Patent, is:

1. In combination with a bottle-cork, a corkscrew having an open or ring handle and an attachment connecting said corkscrew with said cork, said attachment comprising a body-portion extending along the top of the cork and outwardly beyond the edge of the same, a securing prong integral with the inner part of said body-portion entered into the cork and an integral return 120 bent loop-member at the outer end of said body-portion creating a loop receiving the upper end of the ring-handle of and securing the corkscrew in a vertically suspended 125 position, the entering end of the loop being 130

inwardly from the outer end thereof so as to be normally closed when the article is in use and thereby prevent the accidental escape of the corkscrew from the said attachment; 5 substantially as set forth.

2. In combination with a bottle-cork, a corkscrew having an open or ring handle and an attachment connecting said corkscrew with said cork, said attachment comprising a body-portion extending along the top of the cork and outwardly beyond the edge of the same, means at the inner end of said body-portion securing the same to the cork and an integral return bent loop-member at the outer end of said body-portion creating a loop receiving the upper end of the ring-handle of and securing the corkscrew in a vertically suspended position, the inner end of said return member being 10 extended inwardly between said body portion and the top of the cork to prevent the accidental escape of the corkscrew from the attachment; substantially as set forth.
- 15 20 25 3. In combination with a bottle-cork, a

corkscrew having an open or ring handle and an attachment connecting said corkscrew with said cork, said attachment comprising a body-portion extending along the top of the cork and outwardly beyond the 30 edge of the same, means at the inner end of said body-portion securing the same to the cork and an integral return bent loop-member at the outer end of said body-portion creating a loop receiving the upper end of the ring-handle of and securing the corkscrew in a vertically suspended position, the inner end of said return member being 35 extended inwardly between said body portion and the top of the cork to prevent the accidental escape of the corkscrew from the attachment; substantially as set forth.

Signed at Alton, in the county of Belknap and State of New Hampshire, this 31 day of March, A. D. 1911.

WILLIAM ROCKWELL CLOUGH.
